United States Patent Office

Des. 217,435
Patented May 5, 1970

217,435

JAR

David William Wire, 26A Fellows Road,
London, NW 3, England

Filed Oct. 23, 1967, Ser. No. 10,736

Claims priority, application Great Britain June 2, 1967

Term of patent 14 years

Int. Cl. D9—01

U.S. Cl. D9—164

FIG. 1 is an elevational view of a jar showing the new design;

FIG. 2 is a top plan view;

FIG. 3 is a bottom plan view; and

FIG. 4 is an elevational view taken at an angle of 45 degrees from the position shown in FIG. 1.

The dominant features of the design reside in the portions shown in full lines.

What is claimed is:

The ornamental design for a jar, as shown and described.
